KETTLE HANDLE

Jack Morgan, Chicago, Ill., assignor to The Grigo-leit Company, Decatur, Ill., a corporation of Illinois

Application January 12, 1949, Serial No. 202

Term of patent 14 years

(Cl. D44—29)

To all whom it may concern:

Be it known that I, Jack Morgan, a citizen of the United States, residing at Chicago, in the county of Cook and State of Illinois, have invented a new, original, and ornamental Design for a Kettle Handle, of which the following is a specification, reference being had to the accompanying drawing, forming part thereof.

Fig. 1 is a top plan view of a kettle handle showing my new design;

Fig. 2 is a side elevational view;

Fig. 3 is an end elevational view; and

Fig. 4 is a cross sectional view taken along the line 4—4 of Fig. 1.

I claim:

The ornamental design for a kettle handle, as shown.

JACK MORGAN.
